LOOM PROTECTION MECHANISM

Carl D. Brown, Hopedale, Mass., assignor to
Draper Corporation, Hopedale, Mass., a corpora-
tion of Maine

Application November 23, 1934, Serial No. 754,519

3 Claims. (Cl. 139—346)

The present invention pertains to loom protection mechanism and has more particular reference to the type of such mechanism wherein a dagger is engageable with a frog for suddenly and forcibly stopping the loom.

It is customary to mount the frog of protection mechanisms so that it can slide along the loom frame, the frog being provided with a cavity which houses a block of resilient rubber material. This block engages between a fixed thrust wall and an end wall of the frog whereby it serves as a cushion to lessen the shock occasioned by engagement of the dagger and frog. As previously constructed, the cushioning block has been of such a size as to substantially fill the frog cavity when unstressed. The block could not be made smaller in cross-section than the cavity as it would then buckle upon being subjected to the stress of bang-off, and would accordingly fail to impart sufficient resistance to movement of the frog.

Considerable difficulty has been experienced with loom frogs, they breaking frequently for no apparent reason. I have found that this breakage may be traced to the cushioning block. That is, the block when compressed in the direction of movement of the frog tends to expand in other directions and, since there is no room in the frog cavity for such expansion, the frog may literally be burst open. I propose to provide a protection mechanism wherein the frog is not subject to bursting as aforesaid and wherein the cushioning block is still supported and guided by the frog cavity so as to prevent lateral buckling of the block.

To the end mentioned the invention is comprised of a construction which includes a slideable frog having a cushioning block in a cavity therein, wherein the cushioning block is comprised of alternate layers of a resilient rubber material and a relatively rigid material, and wherein alternate of the layers are substantially co-extensive in width and height with the cavity, to prevent buckling, while other layers are of lesser extent to thereby provide space for expansion of the rubber layers. In the preferred embodiment, herein disclosed, the relatively rigid layers are formed of leather, and the rigid layers are the ones chosen to have the greater dimensions. The invention in its broader aspects is not, however, limited to this particular embodiment.

The said preferred embodiment is illustrated on the accompanying drawing, of which:

Fig. 1 is a view, partly in section and partly in

elevation, showing the parts in assembled relation;

Fig. 2 is a plan view of the frog with parts thereof broken away and appearing in section; and

Fig. 3 is a perspective view of the novel cushioning member detached from the loom.

The loom which I have selected to illustrate my invention is generally of conventional construction not of the present invention and accordingly it is but fragmentarily illustrated. There is shown a portion of a left hand loom side 1, a protector rod 2 carrying dagger 3, and a frog 4 to be further described. The protector rod is usually carried by the lay (not shown) so that the rod and dagger reciprocate bodily toward and from the front of the loom, which is toward the right, Fig. 1. The dagger normally passes above an engaging piece 5 of the frog but, when protection is required the dagger engages such piece and thereby forcibly arrests movement of the lay.

The loom side is shaped to provide a frog support constituted by flat surfaces 6 and 7 on which the frog can slide forwardly and rearwardly. The rearward limit of movement of the frog may be determined by a stop member 8 which is adjustably fixed to the loom side. Depending wings, as 9, on the frog depend on opposite sides of the loom side and thus guide the frog in its movements. One of these wings may be provided with a nose 10 adapted to engage and move a lever 11 to stop the loom when the frog is moved forwardly.

A vertical thrust wall 12 underlies a portion of the frog and the latter is recessed rearwardly of the thrust wall to form, with the supporting surface 6 and the thrust wall, the conventional cavity 13. The cavity is substantially closed and is occupied by the cushioning member or block of the present invention.

In accordance with the invention, the cushioning member is comprised of separate sheets or layers each of which is positioned in a vertical plane extending widthwise of the loom, which is normal to the direction of movement of the frog. The alternate layers 14, 14 are formed of a resilient rubber material such as that of which frog cushioning blocks were formerly constructed. The remaining layers 15, 15 are formed of a relatively rigid material and I prefer to use leather for this purpose. An additional layer 16 may be added to make the member of proper length to fill the space between the thrust wall 12 and the end wall of the cavity.

Certain of the layers of the cushioning member are substantially co-extensive in width and height with the cavity 13. Such layers engage the walls of the cavity and thereby prevent buckling of the member when compressed. I have shown the leather layers 15 as being so constructed. Other layers are of lesser extent to thereby provide space for expansion of the rubber material. The rubber layers 14 are shown as being of lesser width and height than the frog cavity. Thus, when bang-off occurs and the cushioning member compressed, the rubber layers can expand both vertically and horizontally without imparting any lateral bursting stresses to the frog.

15 It is noted that the protection mechanism may have a similar dagger, frog and cushioning member at the other side of the loom. However, since such parts are practically duplicates of those shown they need not be illustrated or described.

20 The particular embodiment just described is advantageous, for obvious reasons, but it is also obvious that the invention is not limited to the specific construction shown on the drawing.

Having fully disclosed the preferred embodiment of my invention, I claim:

25 1. In a loom protection mechanism, a frog support, a thrust wall, a frog slidably mounted on said support and recessed to form with said support and wall a substantially closed cavity, and a cushion member positioned in said cavity and substantially co-extensive in length therewith, said member being comprised of alternate layers formed respectively of a resilient rubber material and a relatively rigid material, each of said layers 30 being positioned normal to the direction of movement of the frog and certain of said layers being

co-extensive in width and height with said cavity while other of said layers are of lesser extent to thereby provide spaces into which the rubber layers expand upon compression of the said member.

2. In a loom protection mechanism, a frog support, a thrust wall, a frog slidably mounted on said support and recessed to form with said support and wall a substantially closed cavity, and a cushion member positioned in said cavity and substantially co-extensive in length therewith, 5 said member being comprised of alternate layers formed respectively of a resilient rubber material and of leather, each of said layers being positioned normal to the direction of movement of the frog and certain of said layers being co-extensive in 10 width and height with said cavity while other of said layers are of lesser extent to thereby provide spaces into which the rubber layers expand upon compression of the said member.

3. In a loom protection mechanism, a frog 20 support, a thrust wall, a frog slidably mounted on said support and recessed to form with said support and wall a substantially closed cavity, and a cushion member positioned in said cavity and substantially co-extensive in length there- 25 with, said member being comprised of alternate layers formed respectively of a resilient rubber material and a relatively rigid material, each of said layers being positioned normal to the direction of movement of the frog, said rigid layers 30 being co-extensive in width and height with said cavity while said rubber layers are of lesser extent to thereby provide spaces into which the rubber layers expand upon compression of the said member. 35
